US00D757350S

(12) **United States Design Patent**
Levy et al.

(10) **Patent No.:** US D757,350 S
(45) **Date of Patent:** ** May 24, 2016

(54) **LIGHTING FIXTURE**

- (71) Applicant: **KONINKLIJKE PHILIPS N.V.**, Eindhoven (NL)
- (72) Inventors: **Jonathan Stuart Levy**, Somerville, MA (US); **Michael Fiorino**, Billerica, MA (US); **Chad Lockart**, Reading, MA (US)
- (73) Assignee: **KONINKLIJKE PHILIPS N.V.**, Eindhoven (NL)
- (**) Term: **14 Years**

(21) Appl. No.: **29/495,438**(22) Filed: **Jul. 1, 2014**(30) **Foreign Application Priority Data**

Jan. 7, 2014 (EM) 002493676-0001

(51) **LOC (10) Cl.** **26-99**

Primary Examiner — Kevin Rudzinski

Assistant Examiner — Sean D Lough

(57) **CLAIM**

The ornamental design for the lighting fixture, as shown and described.

DESCRIPTION

FIG. 1 is a perspective view showing my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines are included for the purpose of illustrating portions of the lighting fixture that form no part of the claimed design.

1 Claim, 3 Drawing Sheets(56)
